(57) **CLAIM**

The ornamental design for a drug applicator with massage head and charging station, as shown and described.

DESCRIPTION

FIG. 1 is a right side perspective view of a drug applicator with a massage head and a charging station in accordance with the present design in a fully assembled state;

FIG. 2 is a left side perspective view thereof;
FIG. 3 is a right side elevation view thereof;
FIG. 4 is a left side elevation view thereof;
FIG. 5 is a top side elevation view thereof;
FIG. 6 is a bottom side elevation view thereof;
FIG. 7 is a top end elevation view thereof;
FIG. 8 is a bottom end elevation view thereof;
FIG. 9 is a right side perspective view of the drug applicator with the massage head in accordance with the present design in a partially assembled state without the charging station;
FIG. 10 is a left side perspective view thereof;
FIG. 11 is a right side elevation view thereof;
FIG. 12 is a left side elevation view thereof;
FIG. 13 is a top side elevation view thereof;
FIG. 14 is a bottom side elevation view thereof;
FIG. 15 is a top end elevation view thereof;
FIG. 16 is a bottom end elevation view thereof;
FIG. 17 is a right side perspective view of the charging station of the drug applicator in accordance with the present design without the drug applicator and the massage head;
FIG. 18 is a left side perspective view thereof;
FIG. 19 is a right side elevation view thereof;
FIG. 20 is a left side elevation view thereof;
FIG. 21 is a top side elevation view thereof;
FIG. 22 is a bottom side elevation view thereof;
FIG. 23 is a top end elevation view thereof;
FIG. 24 is a bottom end elevation view thereof;
FIG. 25 is a right side perspective view of the massage head of the drug applicator in accordance with the present design without the drug applicator and the charging station;
FIG. 26 is a left side perspective view thereof;
FIG. 27 is a right side elevation view thereof;
FIG. 28 is a left side elevation view thereof;
FIG. 29 is a top side elevation view thereof;
FIG. 30 is a bottom side elevation view thereof;
FIG. 31 is a top end elevation view thereof; and,
FIG. 32 is a bottom end elevation view thereof.
